Jas. F. Williamson

UNITED STATES PATENT OFFICE.

GEORGE WEIGAND, OF MINNEAPOLIS, MINNESOTA.

MATCH-SAFE.

SPECIFICATION forming part of Letters Patent No. 570,859, dated November 3, 1896.

Application filed June 27, 1896. Serial No. 597,227. (No model.)

To all whom it may concern:

Be it known that I, GEORGE WEIGAND, a citizen of the United States, residing at Minneapolis, in the county of Hennepin and State 5 of Minnesota, have invented certain new and useful Improvements in Match-Safes; and I do hereby declare the following to be a full, clear, and exact description of the invention, such as will enable others skilled in the art to 10 which it appertains to make and use the same.

My invention has for its object to provide an improved match safe or stand adapted especially for use at cigar-counters and similar places, where it is desired to effect an 15 economy in the use of matches.

To this end my invention comprises the novel devices and combinations of devices hereinafter described, and defined in the 20 claims.

The preferred form of my invention is illustrated in the accompanying drawings, wherein, like letters referring to like parts throughout the several views—

Figure 1 is a perspective view showing my 25 improved match safe or stand. Fig. 2 is a plan view of the same. Fig. 3 is a vertical section taken on the line $x^3 x^3$ of Fig. 2, and Fig. 4 is a vertical section taken on the line $x^4 x^4$ of Fig. 2.

The body of the case or stand is in the form 30 of a box or shell a , which in cross-section is oblong. The bottom or lower end of this body-section a is left open, and, as shown, is provided with a bell-mouth or flaring base a' , and the upper or match-discharging end of 35 the same is formed with converging walls a^2 , which terminate short of each other to form a slot a^3 , through which the matches may be discharged one by one. As shown, these 40 converging walls a^2 are formed on lines which represent a double or compound curve, and the ends of the slot a^3 are somewhat enlarged, as shown at a^4 , to permit the ready passage of the friction ends of the matches.

In order to give access to the matches, so 45 that they may be forced by the fingers, or, rather, by a finger and the thumb, through the slot a^3 , the upper edges of the curved or converging wall ends a^2 are notched or cut away, as shown at a^5 . As shown, the base portion 50 a' is provided with a pair of transverse end rods a^6 , which stand outward from the lines

formed by the inner surfaces of the end walls of the body-section a .

The matches z within the case or body section a are spring-pressed to move toward the slot a^3 of said case by means of a follower-plate b , which works freely within the section a and is spring-pressed by a pair of coiled springs b' , the lower ends of which 60 bear against a resistance plate or bar b^2 . Preferably the springs b' should be soldered or otherwise rigidly secured to the follower-plate b at their upper ends, and likewise secured to the resistance-plate b^2 at their lower 65 ends.

The resistance plate or bar b^2 is provided at its ends with catch-springs b^3 , which have lips or lugs b^4 , adapted to engage with the cross-bars a^6 of the base-section a' to remov- 70 ably secure the said resistance-plate b^2 in the lower open end of the case-section a . Obviously by pressing the spring-catches $b^3 b^4$ toward each other the said resistance-plate b^2 , together with the springs b' and follower- 75 plate b , may be readily inserted into working position within the match-safe or removed therefrom. These parts should of course be removed to permit the case to be filled with matches, and then should be placed in 80 working position, as indicated in the drawings. As the matches are used or removed one by one from the match safe or stand the follower b will of course be gradually forced upward, so as to always keep the upper 85 matches crowded into the narrow portion or upper end of the converging section of the safe; but under this action the matches will not be forced through the slot a^3 . On the contrary, the matches will become locked or 90 jammed together just below the slot a^3 . However by applying a finger and thumb to the upper match or matches which are exposed at the finger-notches a^4 the matches may be readily removed from the case one by 95 one.

It should be understood that while I have shown and described the improved form of my invention as in the form of a match-safe adapted to be stood upon a counter or stand 100 so far as the broad principles of my invention are concerned the device might take various forms.

It will also be understood that while I have

described my invention as designed for a match-safe, and while this is the purpose for which it is best adapted, yet the same might be employed for other purposes, such, 5 for instance, as a tooth-pick holder.

What I claim, and desire to secure by Letters Patent of the United States, is as follows:

- 10 1. A match-safe or similar device, formed at its match-discharging end with converging walls which terminate short of each other to form a slot through which the matches may be discharged, one by one, a spring-pressed follower-plate working against the matches in said safe, a removable resistance plate or bar in the open end of said safe, and one or more springs compressed between said follower-plate and said resistance-plate, substantially as described.
- 15 2. A match-safe or similar device formed at its match-discharging end with converging walls which terminate short of each other to form a slot and are provided with finger-

notches, a spring-pressed follower-plate working against the matches in said safe, a 25 removable resistance plate or bar closing the open end of said safe, and a pair of springs secured to and compressed between said follower-plate and said resistance-plate, substantially as described.

3. The combination with the body-section *a* formed with curved converging walls *a*² terminating short of each other to form the slot *a*³ and provided with finger-notches *a*⁴, the base *a'* having cross-rod *a*⁶, the follower-plate *b*, the resistance plate or bar *b*², the springs *b'* secured to said plates *b* and *b*², and the spring *b*³, *b*⁴ coöperating with said bars *a*⁶, substantially as described.

In testimony whereof I affix my signature 40 in presence of two witnesses.

GEORGE WEIGAND.
